MACHINES AND THE LIKE

Peter H. Voorlas, Racine, Wis.

Application January 27, 1949, Serial No. 525

Term of patent 14 years

(Cl. D26—13)

To all whom it may concern:

Be it known that I, Peter H. Voorlas, a citizen of the United States, residing at Racine, county of Racine, State of Wisconsin, have invented a new, original, and ornamental Design for a Foot Treadle Control for Sewing Machines and the like, of which the following is a description, reference being had to the accompanying drawings, forming a part thereof.

Fig. 1 is a side elevational view of a foot treadle control for sewing machines and the like, showing my new design;

Fig. 2 is a top plan view; and

Fig. 3 is a front elevational view thereof.

I claim:

The ornamental design for a foot treadle control for sewing machines and the like, substantially as shown.

PETER H. VOORLAS.
